RAIL FOR TRANSPORTING HANGERS OR CARRIAGES AND SWITCHES THEREFOR

Caesar A. Calder, Verona, N. J.

Application May 26, 1950, Serial No. 164,399

9 Claims. (Cl. 104—191)

1

This invention relates to rails for transporting hangers or carriages and switches therefor. More particularly, this invention relates to a main line rail on which hangers or carriages may be moved and a secondary line rail disposed at an angle to the main line rail, and switch means to permit hangers or carriages to be moved either along the main line rail or from the secondary line rail to the main line rail, or from the main line rail to the secondary line rail.

Usually the secondary line rail is at a higher level than the main line rail. In accordance with the present invention a curved switch rail is pivoted to the secondary line rail about the axis of the latter and it has a tapered end portion adapted to rest on the main line rail when said switch rail is swung down about its pivot, to permit switching of hangers or carriages from the main line to the secondary line and back, and said switch rail being swingable upwardly to the plane or level of the secondary line rail and away from the main line rail to permit movement of hangers or carriages along the main line rail without being switched to the secondary line rail.

In accordance with one form of this present invention the switch rail normally rests on the main line rail but may be lifted, releasable means being provided to retain the switch rail in raised or lifted position when it is swung upwardly, and means being further provided to limit the upward swinging movement of the switch rail. In accordance with another form of the invention the switch rail is biased upwardly away from the main line rail by a spring, means being provided to limit the upward movement of the switch rail to a horizontal plane, the construction being such that if a hanger or carriage supporting garments or any other articles are moved along the secondary line onto the switch rail said switch rail, due to the weight imposed thereon, will drop to permit said hanger or carriage to be switched on to the main line rail, and when weight is removed from the switch rail, said biasing means will again raise said switch rail to horizontal position.

Yet another object of this invention is to provide a switch rail of the character described comprising a tube, one end of which is cut away at its underside and upper side to straddle and fit over a tubular main line rail, so as to facilitate movement of hangers or carriage wheels from the switch rail onto the main line rail and vice versa.

Yet another object of this invention is to provide a strong, rugged and durable construction of

2

the character described which may either be mounted on brackets, supported on a vertical pipe, or which may be mounted on ceiling suspension sets and which shall be relatively inexpensive to manufacture, easy to install and shall be sure and positive in operation and yet practical and efficient to a high degree in use.

Other objects of this invention will in part be obvious and in part hereinafter pointed out.

10 The invention accordingly consists in the features of construction, combinations of elements, and arrangement of parts, which will be exemplified in the construction hereinafter described, and of which the scope of invention will be indicated in the following claims:

In the accompanying drawings in which is shown various illustrative embodiments of this invention,

20 Fig. 1 is a perspective view of a rail switch system embodying the invention and showing the switch rail contacting the main line rail;

Fig. 2 is a view similar to Fig. 1 but showing the switching rail lifted;

25 Fig. 3 is a longitudinal cross-sectional view through the pivotal connection between the switch rail and the secondary line rail;

Fig. 4 is a partial, top plan view of the construction shown in Fig. 3 with parts broken away and in cross-section;

30 Fig. 5 is a cross-sectional view taken on line 5—5 of Fig. 3;

Fig. 6 is a cross-sectional view taken on line 6—6 of Fig. 3;

35 Fig. 7 is a cross-sectional view taken on line 7—7 of Fig. 3;

Fig. 8 is a side elevational view showing the outer end of the switch rail mounted on the main line rail;

40 Fig. 9 is a cross-sectional view taken on line 9—9 of Fig. 8;

Fig. 10 is a cross-sectional view taken on line 10—10 of Fig. 8;

45 Fig. 11 is a top plan view of the outer end of the switch rail;

Fig. 12 is a bottom plan view of the outer end of the switch rail;

Fig. 13 is a view similar to Fig. 3 but illustrating a modified construction in which the switch rail can remain either in a down position resting on the main line rail or is returned in a raised position away from the main line rail;

50 Fig. 14 is a partial top view of the construction shown in Fig. 13, with parts broken away and in cross-section;

55

Fig. 15 is a cross-sectional view taken on line 15—15 of Fig. 13;

Fig. 16 is a perspective view showing the switch system and illustrating one means of supporting the main and secondary line rails by means of brackets supported on a pipe; and

Fig. 17 is a view similar to Fig. 16 but showing the switch system supported on ceiling sets.

Referring now in detail to the drawing and particularly to Fig. 16, numeral 10 designates apparatus embodying the invention, comprising a vertical supporting stanchion or pipe 11. Attached to the pipe 11 by means of brackets 13 is an outwardly extending arm 14. The arm 14 is formed with a vertical sleeve 15 at its outer end. Extending through the sleeve 15 is an upper screw threaded end portion 16 of a hook shaped support 17. Nuts 16a screwed to the threaded portion 16 serve to adjust the height of the hook 17 relative to the arm 14. The support 17 is formed with an offset hook portion 18 having an upwardly extending vertical finger 19. Also fixed to the pipe 11 at a level lower than the arm 14, by means of brackets 20 is an arm 21 extending at right angles to the arm 14. At the outer end of the arm 21 is a vertical sleeve 22. Extending upwardly through said sleeve 22 is the screw threaded portion 16 of another hook shaped member 17. The hook 17 has an offset hook portion 18 provided with an upwardly extending finger 19 for the purpose hereinafter appearing.

Supported by the support 17 on the arm 14 is a horizontal secondary line rail 23. The rail 23 comprises a tubular member 24 having an outer end 25. Mounted on the outer end of tube 24 is a junction member 26 comprising an intermediate cylindrical portion 27 formed at its underside with an upwardly extending blind drilled hole 28 receiving the finger 19 of the hook 18 which forms part of the support 17 attached to the arm 14. The cylindrical portion 27 is formed with a screw threaded opening 29 communicating with the opening 28 and receiving a set screw 30 adapted to press against and clamp the finger 19. Extending from one end of the cylindrical portion 27 is a reduced flange 31 which fits within the outer end of the tube 24. Extending from the flange 31 is an axial screw threaded stud 32 projecting axially into the tube 24. Screwed on the stud 32 is an internally screw threaded ferrule 33 having a tapered or conical outer surface 34. Surrounding the stud 32 and part of the ferrule 33 is a longitudinally split sleeve 35 having a tapered or conical inner surface 36. The split sleeve 35 is disposed within the tube 24. It will now be understood that upon turning member 26 in one direction the ferrule 33 will be moved inwardly toward the flange 31 to expand the split sleeve 35 to press the same against the inner surface of the tube 24. The ferrule 33 will be restrained from turning due to friction with the sleeve. In this manner the member 26 may be firmly attached to the secondary rail 24.

Extending from the intermediate cylindrical portion 27 in the direction opposite to the stud 32 is an axial stud or pin 40. The pin 40 is of greater length than the stud 32 and extends in a direction opposite therefrom. Received on the pin 40 and contacting one end of said intermediate portion 27 is an annular sleeve or ring 41 having the same outer diameter as said portion 27. It is formed with an axial through opening 42 through which the pin 40 passes. It is also formed with a radial screw threaded opening 43 to receive a set screw 44 which fixes the

member 41 against rotation relative to member 26. Said member 41 is furthermore formed at its outer end with a portion 45 of somewhat reduced diameter. Fixed to the outer end of said portion 45 and extending outwardly therefrom is a pin 50. The outer end of said portion 45 may be drilled and one end of the pin force fitted into the drilled hole as at 51. Thus the portion 52 of the pin projects outwardly therefrom in a direction parallel to the axis of the stud 40.

Swingingly mounted on the pin or stud 40 is a switch rail 55. Said switch rail comprises a tube having a straight portion 56 at one end, an intermediate curved portion 57 and a straight outer end 58 at the opposite end. The portion 56 has its outer end 59 received on the flange 45. Disposed within the tubular portion 56 is an inner sleeve 60 formed with a through opening 61 through which the pin or stud 40 passes. The sleeve 60 is fixed to the tube 56 by means of screws 63 so that said sleeve will rotate with the tube. The end of the sleeve 60 adjacent the sleeve 41 is formed with a reduced flange extension 65 contacting said sleeve 41 and forming an annular surface 66 spaced from said portion 45 of the member 41. The end 66 of the sleeve 60 is drilled as at 67 and inserted therein is one end of a pin 68 which projects from said surface and overlaps the projecting pin portion 52. The pins 68 and 50 are equal distances from the axis of the stud or pin 40 so that when the switch rail 55 is swung upwardly or in a counterclockwise direction, looking at Figs. 1 and 2, pin 68 will contact pin portion 52 to limit upward movement of the switch rail to a horizontal position in the plane of the secondary rail 23, as shown in Fig. 2 of the drawing.

Means is provided to bias the switch rail 55 upwardly to the position shown in Fig. 2. To this end there is received on the outer end of the pin or stud 40 a collar 70 fixed thereto by means of a set screw 71. Interconnecting the collar 70 with the outer end 72 of the sleeve 60 is a coil torsion spring 73. One end of the torsion spring is fixed in the collar 70 and is anchored in said position. The opposite end is attached to the sleeve 60 which in turn is attached to the tubular portion 56 of the switch rail 55, and the torsion spring tends to move the switch rail 55 upwardly and retains the switch rail in its up position.

Referring now to the outer end 58 of the switch rail 55, its underside is cut away in a plane inclined to the plane of the axis of said switch rail, to form a V-shaped notch 75. The upper side of said end 58 is also cut away on a plane inclined to the axis of said switch rail to form a top V shaped notch 76. The inclination of the plane of the notch 76 is greater than the inclination of the plane of the notch 75. It will be noted that the notches 75 and 76 form a pair of bifurcated ends 78 which straddle the pipe or main line rail 80 supported by member 17 which is attached to the arm 21, as shown in the drawing. The pipe 80 is formed with a pair of shallow drilled openings 81 which underlie the pointed ends of the bifurcated portions 78.

The main line rail may comprise a plurality of pipes 80 in alignment and they may be attached together by a joint 85 formed with an opening at its underside to receive the finger 19 of offset support 17 which is attached to the arm 21. (The joint 85 may be similar to the construction shown in application of Stephen Speckhart, Serial No. 788,853, filed on November 29, 1947 for Flush Coupling Means.) Said pipes 80 may be sup-

ported by additional hook shaped suspension members 86. It will now be understood that hangers or carriages may move along the main line rail 80 without being disturbed by the switch rail which is in an up position. However, if a hanger or a carriage moves from the secondary line rail on to the switch rail 55, said switch rail will be depressed due to the weight of the hanger or carriage, to the position shown in Fig. 1 and in the full line position of Fig. 16 so that the carriage or hanger may be switched on to the main line rail.

In Figs. 13, 14 and 15 there is shown a modified form of the invention which may be termed a single switch system. In this construction there is likewise provided a secondary line rail 24 mounted on a support 17 which engages the portion 27 of a member 26. Member 26 is likewise provided with a stud or pin 40 and with a sleeve 60 fixed to a switch rail 55. However, in the modification of Fig. 13 there is fixed on the outer end of the pin 40 a collar 90 fixed thereto by a set screw 92. Interposed between the collar 90 and the sleeve 60 is a coil compression spring 93. Fixed to the reduced portion 45 of member 41 is a pin 95. Also fixed to said portion at a position spaced from pin 95 is a second pin 96 having a rounded head 97 projecting from said portion 45. Fixed to the adjacent end of the sleeve 60 is a pin 99 having a rounded projecting portion 99 overlapping the rounded portion 97. The switch rail 55 in the modification of Figs. 13, 14 and 15 rests on the main line rail. However, it may be swung upwardly and when that is done the projecting rounded pin portion 99 contacts the projecting rounded pin portion 97, thereby moving the switch rail 55 to the left, looking at Fig. 13, against pressure of spring 93, a sufficient distance to permit the pin 99 to bypass the pin 97, at which time the switch rail is moved to the right by spring 93. When the pin 99 strikes the pin 95 further upward movement of the switch rail is prevented. When the switch rail is then released, pin portion 99 will contact the opposite side of the pin 97 and the switch rail will remain in a horizontal plane at the level of the secondary rail. The compression spring 93 keeps the sleeve 60 biased toward member 41. When the switch rail 55 is in its up position, garment hangers or carriages may be switched in either direction along the main line rail. When it is desired to switch hangers or carriages from the secondary line rail on the main line rail, member 55 is swung downwardly thereby pressing the switch rail to the left and pressing the spring 93 to permit rounded pin 99 to bypass rounded pin 97. Then the switch rail will drop until its outer end contacts the main line rail. In such position garment hangers or carriages may be switched either from the secondary line rail to the main line rail, or vice versa.

The switch rails may extend in either direction, that is, either to the left as shown in Fig. 16, or to the right as shown in Fig. 17. Furthermore, instead of supporting the main line rail and the secondary rail by means of a vertical supporting rod and arms, said rails may be supported by means of hook members 17 attached to brackets 100 attached to the lower ends of pipes 101, the upper ends of which are attached to brackets 102 which may be fixed to a ceiling.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention I claim as new and desire to secure by Letters Patent:

1. In combination, a tubular rail, a member attached to one end of said rail and provided with a stud extending in the direction away from the rail and being coaxial therewith, a tubular switch rail having one end receiving said stud, a sleeve fixed within said end of said switch rail, and said stud being journaled and slidable in said sleeve and extending therebeyond, a collar on the outer end of said stud and a spring interposed between said collar and adjacent end of said sleeve, and rounded pins fixed relative to the opposite end of said sleeve and said member, respectively, positioned to contact and bypass each other upon swinging said switch rail about the axis of said stud, and said spring permitting longitudinal movement of said switch rail relative to said stud as said pins bypass each other.

2. In combination, a tubular rail, a member attached to one end of said rail and provided with a stud extending in the direction away from the rail and being coaxial therewith, a tubular switch rail having one end receiving said stud, a sleeve fixed within said end of said switch rail, and said stud being journaled in said sleeve, a collar on the outer end of said stud and a spring interposed between said collar and said sleeve, a pin attached to said member and being offset from said stud, and a pin fixed to said sleeve and being offset from said stud and overlapping the first pin, and being adapted to contact said first pin upon rotating said switch rail and sleeve relative to said stud.

3. In combination, a tubular rail, a member attached to one end of said rail and provided with a stud extending in the direction away from the rail and being coaxial therewith, a tubular switch rail having one end receiving said stud, a sleeve fixed within said end of said switch rail, and said stud being journaled in said sleeve, a collar on the outer end of said stud and a spring interposed between said collar and said sleeve, a pin attached to said member and being offset from said stud, and a pin fixed to said sleeve and being offset from said stud and overlapping the first pin, and being adapted to contact said first pin upon rotating said switch rail and sleeve relative to said stud, said pins having rounded ends so that upon rotating said switch rail and said sleeve relative to said stud, the pin on the sleeve may bypass the pin on said member, thereby causing the switch rail to move longitudinally of the stud and compressing said spring.

4. In combination, a tubular rail, a member attached to one end of said rail and provided with a stud extending in the direction away from the rail and being coaxial therewith, a tubular switch rail having one end receiving said stud, a sleeve fixed within said end of said switch rail, and said stud being journaled in said sleeve, a collar on the outer end of said stud and a spring interposed between said collar and said sleeve, a pin attached to said member and being offset from said stud, and a pin fixed to said sleeve and being offset from said stud and overlapping the first pin, and being adapted to contact said first pin upon rotating said switch rail and sleeve relative to said stud,

said pins having rounded ends so that upon rotating said switch rail and said sleeve relative to said stud, the pin on the sleeve may bypass the pin on said member, thereby causing the switch rail to move longitudinally of the stud and compressing said spring, and a second pin fixed to said member and spaced from the first pin thereof and adapted to be contacted by the pin on said sleeve to limit angular movement of said switch rail and said sleeve relative to said stud.

5. In combination with a main line rail and a horizontal secondary rail disposed at a level higher than the main line rail, a switch rail having an intermediate curved portion and straight end portions, one end of said switch rail being pivoted coaxially to one end of the secondary line rail, and the other end of said switch rail being movable into engagement with the main line rail, and said switch rail being swingable upwardly to the horizontal plane of the secondary line rail, said switch rail being tubular and said main line rail being tubular and the end of the switch rail which is adapted to contact the main line rail being cut away at its upper and lower sides on planes inclined to the plane of said switch rail, thereby forming a pair of bifurcated ends adapted to straddle the main line rail.

6. In combination with a main line rail and a horizontal secondary rail disposed at a level higher than the main line rail, a switch rail having an intermediate curved portion and straight end portions, one end of said switch rail being pivoted coaxially to one end of the secondary line rail, and the other end of said switch rail being movable into engagement with the main line rail, and said switch rail being swingable upwardly to the horizontal plane of the secondary line rail, said switch rail being tubular and said main line rail being tubular and the end of the switch rail which is adapted to contact the main line rail being cut away at its upper and lower sides on planes inclined to the plane of said switch rail, thereby forming a pair of bifurcated ends adapted to straddle the main line rail, the main line rail being formed with shallow recesses underlying the pointed ends of said bifurcated portions.

7. In combination, a tubular rail, a member provided with clutch means to engage one end of said tubular rail, said member having an outwardly extending stud, a tubular switch rail having one end receiving said stud, means on said member to center the switch rail relative to the stud, a sleeve within said switch rail and fixed thereto and having a through opening through which said stud extends, said stud extending beyond said sleeve, a collar fixed to the outer end

of said stud, a coil compression spring interposed between the collar and the sleeve, releasable means to retain said switch rail in one angular position and means to positively limit movement of the switch rail relative to said member in another angular position of said switch rail.

8. In combination, a secondary line rail provided with an axial stud, a tubular switch rail having an intermediate curved portion and straight end portions, one end portion of the switch rail receiving said stud, a sleeve within said end of said switch rail and fixed thereto and slidably receiving said stud, spring means to press said switch rail toward said secondary rail, the main line rail being at a level below the secondary line rail and at an angle thereto, and the opposite end of said switch rail being adapted to engage said main line rail when said switch rail is swung downwardly, and said opposite end of said switch rail being movable away from the main line rail upon swinging the switch rail upwardly about the axis of the said stud.

9. In combination, a secondary line rail provided with an axial stud, a tubular switch rail having an intermediate curved portion and straight end portions, one end portion of the switch rail receiving said stud, a sleeve within said end of said switch rail and fixed thereto, spring means to press said switch rail toward said secondary rail, the main line rail at a level below the secondary line rail and at an angle thereto, and the opposite end of said switch rail being engageable with said main line rail when said switch rail is swung downwardly, and said opposite end of said switch rail being movable away from the main line rail upon swinging the switch rail upwardly about the axis of said stud, and means to retain said switch rail in raised condition, and means to limit upward swinging movement of said switch rail relative to said secondary line rail.

CAESAR A. CALDER.
